UNITED STATES PATENT OFFICE.

ALBA E. STONE, OF EVERETT, MASSACHUSETTS, ASSIGNOR TO UNITED SHOE MACHINERY CORPORATION, OF PATERSON, NEW JERSEY, A CORPORATION OF NEW JERSEY.

PULLING-OVER MACHINE.

Application filed January 17, 1921. Serial No. 437,786.

To all whom it may concern:

Be it known that I, ALBA E. STONE, a citizen of the United States, residing at Everett, in the county of Middlesex and State of Massachusetts, have invented certain Improvements in Pulling-Over Machines, of which the following description, in connection with the accompanying drawings, is a specification, like reference characters on the drawings indicating like parts in the several figures.

This invention relates to machines for use in the manufacture of boots and shoes for pulling uppers over lasts, and has more particularly in view improvements in the upper pulling means of such machines.

In pulling-over machines for use on adults' shoes, for example shoes of the welt or McKay type, the opposite side grippers usually comprise, at each side of the shoe, a pair of gripper jaws for gripping the upper substantially at the location of the tip seam and another pair of jaws for gripping the upper farther rearwardly at the ball of the shoe. A machine thus equipped, however, is impractical for use on shoes of the smaller sizes, such as children's shoes, since the rear pairs of jaws would operate on the upper so far from the toe of the shoe as to interfere with the proper pulling over of the upper, and for the further reason that it is difficult to present such a shoe properly to the machine without positioning portions of the margin of the upper within the rear pairs of jaws. It has therefore been the practice to provide different machines for adults' work and for children's work, the adults' machine being known as a five-pincer machine and the children's machine as a three-pincer machine. While the difference between these machines involves substantially nothing more than a substitution of different side gripper mechanisms, the time required in making such a change renders it impractical, under ordinary conditions, to use the same machine for both adults' work and children's work. This has imposed a substantial limitation upon the use of the pulling-over machine, particularly in factories making both adults' and children's shoes where the production of one or the other of

these different kinds of shoes is not sufficiently large to warrant the maintenance of a special machine for that work.

55

One object of this invention, among others, is to provide a construction whereby the same machine may be used on both adults' and children's shoes. To this and other ends, a feature of the invention consists in a novel construction of gripper mechanism having gripper jaws which may be rendered either operative or inoperative at the will of the operator. As applied to a machine such as above described having front and rear pairs of side gripper jaws, the invention provides a construction whereby the rear pairs of jaws may be rendered inoperative to pull an upper without affecting the operation of the front pairs of jaws. In the construction shown the desired result is effected by the provision in each side gripper mechanism of a device which is readily movable into or out of position to prevent the rear pair of jaws from gripping the upper. In using the five-pincer machine on children's work the margin of the upper may thus be permitted to extend within the rear pairs of jaws, as most convenient in presenting the upper properly to the other gripper jaws of the machine, without the undesirable result of pulling the upper in locations so far rearwardly from the toe end of the shoe. The invention thus renders the five-pincer pulling-over machine practically a universal machine for both adults' and children's work.

75

80

85

A further feature of the invention consists in a novel construction and arrangement whereby improved results are secured in the operation of drawing the upper inwardly over the bottom of the last. In its illustrative embodiment the invention provides a novel organization in which the side grippers in their overdrawing movements are turned in such manner as to cause the rear portions of the gripper jaws to move farther inwardly than the front portions, thus increasing the extent of the pull on portions of the upper at the rear of the jaws with a twisting effect to tighten the upper both inwardly and forwardly over the shoulder at the junction of the ball and the shank of the shoe. In the machine shown

90

95

100

this result is effected in the use of the machine with the rear pairs of side gripper jaws inoperative, the turning of the side grippers resulting from the fact that the pressure for forcing each side gripper inwardly over the bottom of the shoe is applied at the rear of the line of pull through the front gripper jaws. In such operation of the machine on children's shoes it is found that the upper is drawn into closer conformity to the last than heretofore along the sides of the shoe at the rear of the ball line, in such manner that the customary use of hand pincers for pulling the upper inwardly at the sides prior to side lasting or to sewing the upper to the insole is rendered unnecessary.

The above and other features of the invention, including certain details of construction and combinations of parts, will now be described with reference to the accompanying drawings and pointed out in the claims.

For purposes of illustration the invention is herein shown as embodied in a type of machine the general organization of which is substantially like that shown in United States Letters Patent No. 1,030,522, granted on June 25, 1912 upon an application of R. F. McFeely, but it will be understood that in many of its novel aspects the invention is not limited to machines of that particular type. In view of the detailed disclosure in said prior patent of the general organization of the machine, the present description will be confined only to such parts of the structure as it is necessary to refer to for an understanding of the invention.

40 In the drawings:

Fig. 1 is a view partly in side elevation and partly in section showing the upper pulling means of a machine of the illustrative type as equipped with the improvements of this invention and illustrating the operation of the machine in pulling a child's shoe,

Fig. 2 is a side elevation of a portion of one of the side grippers with the cover plates removed,

Fig. 3 is a vertical section on the line 3-3 of Fig. 2,

Fig. 4 is a section on the line 4-4 of Fig. 2, and

Fig. 5 is a section substantially parallel to the plane of the shoe bottom through the grippers and associated parts and illustrating the character of the overdrawing operation.

It will be understood that in machines of the illustrative type the upper of the shoe is pulled over the last against the resistance of a sole rest 2 by means of a toe gripper and opposite side grippers connected respectively to a toe updraw lever 4 and

opposite side updraw levers 6 to which operative movement is imparted yieldingly through springs 8 and 10 by the movement of cam slides 12 and 14 operated respectively by cams 16 and 18 on the cam shaft 20. The toe gripper comprises a gripper casing 22 on which are mounted a pair of gripper jaws 24, and a gripper bar 26 connected at its upper end to the updraw lever 4 and operated in the usual manner first to close the jaws on the upper and then to move the jaws and the casing to pull the upper. The side grippers in the illustrative type of machine present at each side of the shoe a front and a rear pair of gripper jaws 28 arranged respectively to engage the upper of an adult's shoe substantially at the location of the tip seam and farther rearwardly at the side of the forepart, the two pairs of jaws at each side being mounted respectively on separate gripper casings 30 and 32 slidably mounted on a single gripper bar 34 which is connected at its upper end to the corresponding side updraw lever 6. The details of the side gripper mechanisms will be more particularly described hereinafter, but it will be understood that, similarly to the operation of the toe gripper, the side gripper jaws at each side of the shoe are closed by the movement of their gripper bar 34 which acts subsequently to move the jaws and the casings 30 and 32 to pull the upper. After the upper has been pulled the machine comes automatically to rest to permit inspection of the work and any necessary adjustment.

Upon a subsequent starting of the machine the overdrawing and upper fastening operations are performed, the grippers being forced inwardly over the shoe bottom by overdraw springs 36 and by the assistance also of a toe tacker arm 38 and opposite side tacker arms 40 which are forced inwardly against the respective grippers into position for driving the upper fastening tacks, these arms being provided also with the usual overlaying devices for wiping the upper inwardly and holding it at the tacking points. In their inward movements the several tacker arms press against tripping members 42 on the different grippers, and when the pressure becomes great enough these members are operated to break the connections between the gripper bars and the gripper jaws and permit the jaws to open and release the upper. Following the tacking operation the parts of the machine return to their starting positions.

By reference to Figs. 2 and 3 it will be seen that, similarly to the construction shown in said prior patent, each pair of side gripper jaws comprises a fixed jaw and a pivoted jaw on the associated gripper casing, and that in each of the casings 30 and 32 there is

a closing slide 44 provided with a roll 46 to engage the pivoted jaw and close it on the upper stock through upward movement of the closing slide relatively to its casing. 5 Movable laterally in each of the closing slides 44 is a slide block 48, these blocks receiving the opposite ends of an equalizer bar 50 which is pivoted on a central block 52. The gripper bar 34, which extends downwardly into both casings 30 and 32, carries a pivoted latch 54 which, in the starting position of the machine, is arranged to hook under the block 52, as shown in Fig. 3, the latch being held in operating position by 10 means of a spring plunger 56. When the parts are in this position lugs 58 on the gripper casings are in engagement with portions of the frame of the machine and springs 60 in the gripper bar are under compression between the bar and pins 62 on the gripper casings. The closing slides 44 are thus relieved of upward pressure and are positioned sufficiently low in the casings to permit the jaws to stand in open position. 15 When the gripper bar 34 is moved upwardly upon the starting of the machine, the springs 60 expand while holding the gripper casings in their lowermost position, and the bar thus acts through the latch 54 to raise the block 20 52 and through the equalizer bar 50 and the closing slides to close the pivoted jaws on the upper stock with substantial equalization of pressure of the two pairs of jaws on the stock through the action of the equalizer bar. 25 As soon as the jaws have been closed with sufficient pressure the gripper casings begin to move upwardly with the gripper bar to cause the jaws to pull the upper, the equalizer bar and the relatively movable closing slides and casings permitting relative movement of the different pairs of gripper jaws in proportion to differences in resistance of the different portions of the upper. 30 It will be noted by reference to Fig. 3 that the tripping members 42 on the opposite side grippers are pivoted on the blocks 52 with their lower ends in position to engage the lower hooked ends of the latches 54, and through pressure of the side tacker arms in the overdrawing movement of the grippers the members 42 are operated to 35 push the latches 54 from under the blocks 52, thus releasing the blocks and breaking the connection between the gripper bars and the closing slides 44, which permits the gripper jaws to open and release the upper. 40

For purposes of this invention the rear gripper casing 32 of each side gripper mechanism has dovetailed therein, at the back of the outer cover plate 64, a locking member 66 which may be moved from the full line position shown in Fig. 2 into the dotted line position in which it projects within the opening in the rear closing slide 44 in which the block 48 is mounted, this

block being cut away or recessed on its outer side (Figs. 2 and 4) to admit the locking member. When the locking member is thus in its inner position it serves as a stop to prevent such upward movement of the rear 70 slide 44 relatively to the casing 32 as to close the rear gripper jaws. When the machine is operated under these conditions the rear pair of jaws at each side will not be closed, notwithstanding the fact that the rear jaws and their casing 32 may be moved bodily upward by the action of the equalizer bar 50 which acts as usual to close and operate the front pair of jaws when the gripper bar is moved upwardly. In using the 75 machine on a child's shoe, for example, the margin of the upper may be positioned within both the front and rear pairs of side gripper jaws, as convenient in presenting the shoe to the machine, but the rear pair of 80 jaws at each side will be inoperative to grip and pull the upper and the upper will be pulled only by the front pairs of side gripper jaws. By the manipulation of the locking slides 66 the machine may be changed 85 very quickly for operation either on children's shoes or on adults' shoes. To assist in moving the slides 66 in or out, each slide in the construction shown is provided with a groove 68 to receive the edge of a screw 90 driver or other suitable tool. To insure that the slide will remain in either its inner or its outer position, a spring plunger 70 is provided for engagement with suitable recesses 95 in the back face of the slide. The construction shown is thus simple and convenient and out of the way of other parts of the machine, but it will be understood that the invention is not limited to the details of the mechanism herein illustrated for 100 locking or releasing the closing slide.

It will be understood that in machines of the illustrative type each side gripper mechanism is so mounted on the updraw lever and in the guiding frame that it may turn about an axis extending transversely of the plane of the shoe bottom. When both pairs of gripper jaws are in engagement with the upper there is no substantial turning movement of the gripper one way or the other in the overdrawing operation by reason of the fact that the upper opposes substantially the same resistance to the inward movement of both pairs of gripper jaws. When the rear pair of side gripper jaws, 110 however, is rendered inoperative as above described to adapt the machine, for example, for operation on children's shoes, the work offers no resistance to the inward movement of the rear pair of side gripper jaws in the overdrawing and overlaying operation aside from the resistance to the inward movement of the side gripper as a whole by reason of the engagement of the front pair of jaws 115 with the upper. It will also be evident that 120 125 130

the inward pressure of the side tacker arm against the tripping member 42, which as above explained assists in forcing the gripper inwardly over the shoe bottom, is at the rear of the line of pull through the front pair of jaws. The result is that the pressure against the member 42 serves to turn the gripper about its connection with the updraw lever, swinging the rear portion of 10 the front pair of jaws farther inwardly than the front portion with a twisting effect on the upper stock in such direction as to tighten portions of the upper at the rear of the jaws inwardly and forwardly over 15 the shoulder at the junction of the forepart and the shank of the shoe. This action is assisted, moreover, by the operation of the side overdraw springs 36 which are in engagement respectively with opposite ends 20 of a plate 72 that extends across the gripper, since the rear spring encounters less resistance than the spring at the front end of the plate. The result is that on a child's 25 shoe the upper is pulled more perfectly in conformity to the contour of the last than heretofore, and it is found that when shoes have thus been operated upon by the machine there is no necessity as heretofore for pulling the upper inwardly at the rear of 30 the ball of the shoe preparatory to side lasting or to sewing the upper to the insole.

In using the machine with the rear pairs of side gripper jaws inoperative it is desirable to prevent the driving of the tacks which, in operating on adults' shoes, are driven in position to hold the portions of the upper which are operated upon by the rear pairs of jaws. This may be done by the use of the tack controlling mechanism 35 with which machines of the illustrative type are commonly provided, as shown in United States Letters Patent No. 1,135,957 granted on April 13, 1915 upon an application of R. F. McFeely.

Having described the invention, what I claim as new and desire to secure by Letters Patent of the United States is:—

1. In a machine of the class described, the combination with a gripper having a pair of upper gripping jaws, and operating mechanism to cause said jaws to grip an upper on a last and for effecting relative movement of said jaws and the last in a direction substantially perpendicular to the plane of the last bottom to pull the upper, of means for rendering said jaws inoperative to pull an upper lying between them in the relative movement of said jaws and the last in said direction of pull.

2. In a machine of the class described, the combination with a gripper having a pair of upper gripping jaws, and operating mechanism to cause said jaws to grip and to pull an upper, of a device on said gripper movable into or out of position to render

said jaws inoperative to pull an upper lying between them in the operative movement of said mechanism.

3. In a machine of the class described, the combination with a gripper having a pair of upper gripping jaws, jaw closing connections, and means arranged to operate through said connections to close the jaws and to move them to pull an upper, of a device for rendering said connections inoperative to close the jaws while permitting the jaws to move in the direction of pull.

4. In a machine of the class described, the combination with a gripper having a pair of upper gripping jaws and parts relatively movable to close said jaws on an upper, and operating means for effecting relative movement of said parts to close the jaws and for moving the jaws to pull the upper, of a device on the gripper movable into position to lock said parts against relative jaw closing movement without preventing the normal movement of said operating means.

5. In a machine of the class described, a gripper comprising a pair of upper gripping jaws, a casing on which said jaws are mounted for relative closing movement, a gripper bar movable relatively to the casing and operative in said movement to close the jaws, means for operating said bar first to close the jaws and then to move the jaws and the casing to pull the upper, and a device on said gripper movable into or out of position to prevent in the operative movement of said bar such relative movement of the bar and the casing as to close the jaws on the upper.

6. In a machine of the class described, a gripper comprising a pair of upper gripping jaws, a casing on which said jaws are mounted for relative movement to grip an upper, a closing slide in said casing for effecting relative closing movement of said jaws, a gripper bar connected to said closing slide for operating the slide to close the jaws and for then imparting to the jaws and the casing operative movement to pull the upper, and a member mounted on said casing for movement into or out of position to prevent the jaw closing movement of said slide.

7. In a machine of the class described, the combination with a gripper having a pair of upper gripping jaws, and an updraw lever for operating said gripper to close the jaws and to pull the upper, of a device movable into position to render said jaws inoperative to pull an upper extending between them in the operative movement of said lever.

8. In a machine of the class described, the combination with upper gripping means comprising a plurality of pairs of jaws for gripping an upper on a last, and mechanism for closing said jaws on the upper and for

- effecting relative movement of the jaws and the last to pull the upper, of mechanism for rendering a portion only of said upper gripping means inoperative to pull the upper 5 while permitting relative movement of all of said jaws and the last in the direction of pull.
9. In a machine of the class described, the combination with a plurality of pairs of upper gripping jaws, and operating mechanism for closing said jaws on an upper and for moving them to pull the upper, of a device associated with one of said pairs of jaws and operative independently of the gripping and pulling movements of the other jaws to prevent said pair of jaws from gripping the upper while permitting them to move in the direction of pull. 10
10. In a machine of the class described, the combination with a plurality of pairs of upper gripping jaws and operating mechanisms for the different respective pairs of jaws comprising parts relatively movable to close the jaws and movable together with the 15 jaws to pull an upper, of a device movable into or out of position to lock the parts of one of said operating mechanisms against relative movement for closing its jaws while permitting the normal closing and pulling movements of other operating mechanisms. 20
11. In a machine of the class described, the combination with upper pulling means comprising grippers for engaging an upper at opposite sides of a shoe, and means automatically to close said grippers in the normal cycle of the machine, of means adjustable to vary the extent of engagement of said grippers with the upper lengthwise of the shoe. 25
- 40 12. In a machine of the class described, the combination with upper pulling means comprising opposite side grippers arranged to present at each side of the shoe a plurality of pairs of upper gripping jaws for gripping an upper in different locations lengthwise of the shoe, and power means automatically operative to close said jaws upon the starting of the machine, of means for rendering a pair of said jaws at each 45 side of the shoe inoperative to pull the upper during the normal operation of the other side gripper jaws.
13. In a machine of the class described, the combination with opposite side grippers arranged to present at each side of the shoe front and rear pairs of upper gripping jaws and automatically operative power means for closing said jaws, of a device associated with each of said rear pairs of jaws and movable into position to render said rear jaws inoperative to pull the upper while the upper is pulled by the front pairs of jaws. 55
- 60 14. In a machine of the class described, the combination with opposite side grippers arranged to present at each side of the shoe front and rear pairs of upper gripping jaws and comprising parts relatively movable to close the jaws on an upper and movable together with the jaws to pull the upper, of devices movable into position to prevent relative movement of said parts to close the rear pairs of jaws while permitting the closing and pulling movements of the front pairs of jaws. 70
15. In a machine of the class described, the combination with opposite side grippers arranged to present at each side of the shoe front and rear pairs of upper gripping jaws, and means for operating said grippers for closing the jaws on an upper and for moving the jaws to pull the upper, of devices operative independently of the gripping and pulling movements, of the front pairs of jaws for rendering the rear pairs of jaws either operative or inoperative to grip and pull the upper. 75
16. In a machine of the class described, the combination with opposite side grippers arranged to present at each side of the shoe front and rear pairs of upper gripping jaws and each comprising an operating member and connections between said member and the front and rear pairs of jaws for closing them on an upper, of devices on said grippers movable into position to render the connections to the rear pairs of jaws inoperative to close said jaws while permitting the closing of the front pairs of jaws by the operation of said members. 80
17. In a machine of the class described, the combination with opposite side grippers each having front and rear pairs of upper gripping jaws and including closing slides for the different respective pairs of jaws and a gripper bar to impart jaw closing and upper pulling movements to the jaws through said slides, of members on said grippers movable into position to prevent jaw closing movement of the closing slides for the rear pairs of jaws while permitting the front pairs of jaws to be closed and operated by movement of the gripper bars. 85
18. In a machine of the class described, the combination with a gripper having different pairs of upper gripping jaws, and an operating member for effecting closing movements of the different pairs of jaws, of a member on said gripper movable into or out of position to render one of said pairs of jaws inoperative to grip the work without affecting the gripping of the work by the other pair of jaws. 90
19. In a machine of the class described, the combination with a gripper having different pairs of upper gripping jaws, closing slides for the different respective pairs of jaws, and a gripper bar connected to said slides for closing the jaws, of a device movable into position to prevent jaw closing 95
- 105
- 110
- 115
- 120
- 125
- 130

movement of one of said slides without preventing jaw closing movement of the other slide.

20. In a machine of the class described, the combination with a gripper having different pairs of upper gripping jaws, closing slides for the different respective pairs of gripper jaws, an equalizer between said closing slides, and a gripper bar connected to said equalizer for imparting jaw closing movement to the slides, of a device movable at the will of the operator into or out of position to restrain one of said slides from operative jaw closing movement.

21. In a machine of the class described, the combination with a gripper having different pairs of upper gripping jaws, gripper casings on which said different pairs of jaws are mounted for relative closing movements, closing slides in said casings, and a gripper bar arranged to move the slides relatively to said casings to close the jaws and then to move the slides and the casings together to pull the upper, of a member mounted on one of said casings and movable into or out of position to restrain the corresponding closing slide from closing movement relatively to its casing.

22. In a machine of the class described, the combination with a gripper for engaging an upper on a last, and means for effecting relative movement of said gripper and the last to pull the upper and for then bringing the machine to a stop with the upper under tension, of means for moving the gripper inwardly over the bottom of the last to overdraw the upper upon a subsequent starting of the machine and for imparting to the gripper in its overdrawing movement a turning movement about an axis substantially perpendicular to the plane of the shoe bottom.

23. In a machine of the class described, the combination with a gripper for engaging an upper on a last, and means for effecting relative movement of said gripper and the last to pull the upper, of means for forcing the gripper inwardly over the bottom of the last to overdraw the upper by pressure applied to the gripper in such relation to the line of pull through the gripper jaws as to impart to said jaws in their overdrawing movement a turning movement about an axis transverse to the plane of the shoe bottom.

24. In a machine of the class described, the combination with a gripper for pulling an upper over a last, said gripper being mounted for movement inwardly over the bottom of the last to overdraw the upper, of overlaying and fastening means mounted for movement inwardly over the shoe at the outer side of said gripper and arranged to engage the gripper with inwardly directed pressure in such relation to the line of pull

through the gripper jaws as to impart to said jaws in their overdrawing movement a turning movement about an axis transverse to the plane of the shoe bottom.

25. In a machine of the class described, the combination with opposite side grippers for pulling an upper over a last, of means for moving said grippers inwardly over the bottom of the last to overdraw the upper and for turning said grippers in their overdrawing movement in directions to impart to the rear portions of the gripper jaws movement of greater extent than the front portions.

26. In a machine of the class described, the combination with opposite side grippers for pulling an upper over a last, of means for forcing said grippers inwardly over the bottom of the last to overdraw the upper by pressure applied to each gripper in such relation to the line of pull through the gripper jaws as to impart to the jaws a turning movement to increase the extent of the pull on portions of the upper at the rear of the jaws.

27. In a machine of the class described, the combination with opposite side grippers for pulling an upper over a last, of means for forcing said grippers inwardly over the bottom of the last to overdraw the upper comprising members arranged to engage said grippers on their outer sides with pressure applied to each gripper at the rear of the line of pull through the gripper jaws to impart to the gripper a turning movement to draw portions of the upper at the rear of the jaws inwardly and forwardly over the shoulder at the junction of the ball and the shank of the shoe.

28. In a machine of the class described, the combination with opposite side grippers for pulling an upper over a last, of overlaying and fastening devices mounted for movement inwardly over the shoe at the outer sides of the respective grippers and arranged to engage said grippers with inwardly directed pressure applied to each gripper at the rear of the line of pull through the gripper jaws to impart to the gripper an overdrawing movement including a turning movement to tighten inwardly and forwardly over the last portions of the upper at the rear of said jaws.

29. In a machine of the class described, the combination with opposite side grippers each comprising front and rear pairs of upper gripping jaws, of means for rendering the rear pairs of jaws inoperative to grip the upper while permitting the upper to be gripped and pulled by the front pairs of jaws, and means for imparting to said grippers overdrawing movement by pressure applied to each gripper at the rear of the line of pull through the front pair of jaws to turn said jaws about an axis trans-

verse to the plane of the shoe bottom when the rear pairs of jaws are inoperative.

30. In a machine of the class described, the combination with grippers for pulling an upper in different locations simultaneously including a gripper for engaging the upper substantially at the ball of the last, of operating means for imparting to said gripper a movement to draw the upper 10 inwardly over the bottom of the last accompanied by a turning movement to draw the upper forwardly over the shoulder at the junction of the ball and the shank of the shoe.

15. 31. In a machine of the class described, the combination with grippers for pulling an upper in different locations simultaneously including a gripper for engaging the upper at the side of the last, of means 20 for moving said gripper inwardly to draw the upper over the bottom of the last and for turning it as it is moved inwardly to impart to the rear portions of the gripper jaws a greater extent of inward movement 25 than to the front portions of said jaws.

32. In a machine of the class described, the combination with grippers for pulling an upper in different locations including a gripper for engaging the upper at the side 30 of the last, of power operated means for effecting relative movement of the different grippers and the last to pull the upper and for imparting to said side gripper an inward movement to draw the upper over the 35 bottom of the last and a simultaneous turning movement about an axis extending transversely of the plane of the bottom of the last.

33. In a machine of the class described, the combination with a gripper having a pair of upper gripping jaws, and operating mechanism comprising a member movable to close said jaws on an upper and to effect relative movement of the gripper and a last 45 to pull the upper, of a device arranged to be set prior to the operation of the machine to render said jaws inoperative in response to movement of said member to pull an upper extending between them.

50. 34. In a machine of the class described, the combination with a gripper having a pair of upper gripping jaws, and operating mechanism for closing said jaws on an upper and for effecting in time relation to the closing of the jaws a relative movement of the gripper and a last to pull the upper, of a device movable prior to the operation of the machine into position to prevent said pair of jaws during the movement of said operating 55 mechanism from gripping and pulling an upper extending between them.

55. 35. In a machine of the class described, the combination with a gripper having a pair of upper gripping jaws, an operating member, and mechanism responsive to movement of

said member to close said jaws on an upper and then to effect relative movement of the gripper and a last to pull the upper, of a device movable into position to prevent said pair of jaws during the normal movement of 70 said operating member from pulling an upper extending between them.

36. In a machine of the class described, the combination with a gripper having a pair of upper gripping jaws, an operating member, and mechanism operated by said member to cause the jaws to grip an upper, of a device arranged to be set to prevent said jaws in the movement of the operating member from gripping an upper extending between them. 75

37. In a machine of the class described, the combination with power means for automatically gripping and pulling an upper in locations at different distances respectively from the toe end of a last, of a device movable prior to the operation of the machine into position to prevent the pulling of the upper in one of said locations without affecting the pulling of the upper in the other location. 80 85

38. In a machine of the class described, the combination with upper pulling means comprising upper gripping jaws for gripping and pulling an upper in locations at different distances respectively from the toe end 90 of a last, and operating mechanism for closing said jaws on the upper and for effecting relative movement of the jaws and the last to pull the upper, of a device arranged to be set prior to the operation of 100 the machine to prevent the jaws in one location from pulling an upper extending between them during the pulling of the upper by the jaws in the other location.

39. In a machine of the class described, the combination with upper pulling means comprising upper gripping jaws for gripping and pulling an upper in locations at different distances respectively from the toe end of a last, an operating member, and mechanism responsive to movement of said member to close the jaws on the upper and to move them to pull the upper, of a device movable into position to prevent said mechanism from closing the jaws in one location during the gripping and the pulling of the upper by the jaws in the other location. 105 110 115

40. In a machine of the class described, the combination with upper pulling means comprising upper gripping jaws for gripping and pulling an upper in locations at different distances respectively from the toe end of a last, and operating mechanism including relatively movable jaw closing connections in the different respective locations, of a device movable into position to render the jaw closing connections in one of said locations inoperative to close the jaws during the pulling of the upper by the jaws in the other 120 125 130 location.

41. In a machine of the class described, the combination with upper pulling means comprising a side gripper having front and rear pairs of upper gripping jaws, for gripping the upper materials respectively in different locations lengthwise of the shoe, and operating mechanism for closing said jaws on an upper and for moving them to pull the upper, of a device arranged to be set prior to

the operation of the machine in position to 10 prevent one of said pairs of jaws from pulling an upper extending between them during the pulling of the upper by the other pair of jaws.

In testimony whereof I have signed my 15 name to this specification.

ALBA E. STONE.
